UNITED STATES PATENT OFFICE.

WILLIAM R. CUNNINGHAM, OF BUCYRUS, OHIO, ASSIGNOR TO THE AMERICAN CLAY MACHINERY COMPANY, OF BUCYRUS, OHIO, A CORPORATION.

OFF-BEARING ATTACHMENT FOR BRICK-PRESSES.

No. 927,834.

Specification of Letters Patent.

Patented July 13, 1909.

Application filed April 7, 1908. Serial No. 425,677.

To all whom it may concern:

Be it known that I, WILLIAM R. CUNNINGHAM, a citizen of the United States, residing at Bucyrus, in the county of Crawford and State of Ohio, have invented certain new and useful Improvements in Off-Bearing Attachments for Brick-Presses, of which the following is a specification.

This invention relates to the clay working industry and particularly to a mechanism for removing brick automatically from a dry press brick machine and depositing the same onto a conveyer.

The mechanism herein shown is in the nature of an attachment to a brick machine or press and it is capable of being applied or used in conjunction with any of the well known machines for pressing brick with little or no modification of the construction shown.

The essential object of the invention is to enable the pressed brick to be handled automatically and to overcome the necessity of handling the brick by hand, thereby saving the expense of men to do the work of removing the brick from the machine and depositing the same onto the conveyer.

With this and other objects in view the invention consists of the parts and the constructions and combinations of parts which I will hereinafter describe and claim.

In the accompanying drawings forming part of this specification and in which similar reference characters indicate like parts throughout the several views, Figure 1, is a side elevation, partially in section, of an off-bearing attachment to a dry-press showing in outline a four-mold dry-press brick machine, which is illustrative of one of the many designs that my attachment is to be applied to.

Fig. 1^a is a detail showing the cam and bell-crank lever mechanism for the elevating rods. Fig. 2, is an enlarged detail, in section and plan of one of the lifting-heads showing the adjustable spurs. Fig. 3 is an enlarged

detail of the lower portion of the elevating rod, showing the attachment of the connecting rod, 15. Fig. 4 is a side elevation of Fig. 3. Fig. 5 is a front end elevation of the off-bearing attachment. Fig. 6 is a plan view of

Fig. 1 showing parts broken away. Fig. 6^a is a plan view of a portion of the press table and conveyer and the rack-bar and segmental bell-crank. Fig. 7 is a plan view of Fig. 8. Fig. 8 is a side elevation of a portion of a

conveyer of modified form. Fig. 9 is a modi-

fication of the elevating and turning mechanism, which I will hereinafter describe.

In Fig. 1 I show an outline of a dry-press brick machine of the four-mold type, although this machine may represent any form of brick press having any desirable number of molds. In presses of this type there is usually present a receiving table, 1, which is shown in section, Fig. 1, and a mold box, 2, in which the brick are formed. After the brick are formed they are delivered onto the table by the usual and well known charger, not shown, which pushes the brick from over the mold, after which the charger fills the mold with loose material to be pressed. The charger is not shown but its construction and operation are well known and its function is to deliver the brick into the position shown in full lines in Fig. 1.

By reference to Fig. 6, it will be seen that the table is constructed with slots or openings, 3, 4, 5 and 6 for a four-mold press, but it will be understood that the number of slots or openings may be increased or decreased in accordance with the number of molds used in the press. In said Fig. 6, the molds appear in plan in full lines and the arrangement is such that one mold is used in conjunction with one of the slots or openings in the table, through which openings suitable elevating-heads are designed to pass under the brick and to elevate the same into the dotted positions shown in Fig. 1, as I will hereinafter fully disclose.

As before stated, through each of the openings 3, 4 5 and 6 of the table 1, is designed to operate vertically a lifting-head which is shown in the enlarged detail, Fig. 2, said heads adapted to engage and elevate the brick which have been passed or pushed over the openings, 3, 4 5 and 6 by the charger of the brick press, each of said heads being provided with a number of adjustable spurs, 8. In Fig. 2, I illustrate four of these spurs for each head, although more or less may be used, if desired, the spurs being threaded into the lifting-head and having pointed ends. Each lifting-head is composed of a plate through which the spurs are screwed, said plate having a hub, 9, and being bored and tapped at 10. Each lifting-head is connected with an elevating-rod, 11, which is herein shown in the form of a bar square in cross-section, the upper end of said bar being of reduced thickness and being threaded, as at

12, to permit the elevating-head, to be screwed the proper distance onto the elevating-rod. In order to lock the head and its rod in any position the parts have been adjusted, I employ a nut 13. As shown in Figs. 3 and 4 the lower end of the elevating-rod, 11, is turned spherical at 14, to permit the square bar to turn in the connecting-rod, 15, said connecting-rod having a socket or being designed to fit the spherical end 14, and being slotted from side to side as shown by dotted lines 16, in Fig. 14. To the lower end of the connecting-rod, 15, is a pin, 17, which passes through the bifurcated end, 18, of one arm of a bell-crank lever, 19, said lever having a hub, 20, and a short arm, 21, the outer end of which carries a roller, 22, mounted on a pin, 23.

Referring to Fig. 5, the brick are shown in full lines lying at rest on the table over the openings 3, 4, 5 and 6 after said brick have been pushed out of the brick press by the charger thereof, and it will be observed in said Fig. 5 that I use one elevating-mechanism for each brick. In the present drawings I show my improvement as used in association with a four-mold press, although two, four or six molds are often used and any number of molds may be used without desparting from the spirit of my invention.

Each of the elevating-rods, 11, passes through a sleeve, 24, shown more particularly in Fig. 1, said sleeve being provided with a square hole through its entire length to admit the corresponding elevating-rod, the upper end of said sleeve being provided with a segmental-gear, 25, better shown in Fig. 6, and the lower end of the sleeve being provided with a collar, 26, to prevent the sleeve from rising, said sleeve being also held in position by a bearing, 27, which is a part of the frame, 28, which is supported by uprights, 29 and 30, these uprights being bolted or otherwise fixed to a suitable carriage by the bolts, 31 and 32, which pass through base flanges, 33 and 34, of the uprights and corresponding flanges, 35 and 36, of the carriage, 68, as shown in Fig. 5.

The frame, 28, which is supported by the uprights, 29 and 30, is provided with bearings, 37 and 38, as shown in Fig. 6, which bearings are designed to support the horizontal transversely operating rack-bar, 39, the teeth of said rack being designed to engage with the teeth of the segments, 25, of the sleeve, 24, through which the elevating-rod operates. The rack-bar is shown as having teeth on its opposite sides, the teeth of one side engaging the aforesaid segments and the teeth on the opposite side and herein designated as 41, being designed to mesh in the teeth, 42, of the segmental bell-crank, 43, which is located near one end of the rack-bar. The bell-crank, 43, is provided with a vertically-disposed hub, 44, through which passes

the vertical pin, 45, whose lower end is secured in the hub, 46, which forms a part of the upright, 29, before described. The outer end of the arm, 47, of the bell-crank, 43, is shown enlarged as at 48, and provided with an elongated hole, 49, through which passes a shifting bar, 50, which is horizontally-disposed and has its outer end passing through a boss, 51, which forms a part of a plate, 52, as shown in Fig. 1, said bar, 50, being held in position by a set-screw passing through the boss and engaging the bar. On the shifting-bar, 50, are suitable slip-collars, 54 and 55 which are held in a desired position by screws, 56 and 67, this arrangement affording means for adjusting the collars in proper position to cause the bell-crank, 43, to turn in a horizontal plane about the vertical pin, 45, at the proper time, as I will hereinafter describe.

The base plate, 58, of the machine is secured to an appropriate foundation by bolts, 59, or other suitable means. To the base plate are also bolted the guide-frames 60 and 61 whose upper ends are provided with female guides, 62 and 63, these guides being made in the usual manner of providing two parallel surfaces. I prefer in the present case, to make the upper portion of the guide-frame, 60, in the form of a flat surface, which is arranged at right angles to form the lower wall or guide of the side frame, the upper wall of the guide being bolted parallel with the lower wall by the bolts, 64 and 65.

Bolted to the carriage-frame, 68, by bolts, 69 and 70, passing through the flanges 71 and 72, and through holes in the carriage, 68, are the male guides which are designed to work in the guides, 62 and 63, the two sets of guides furnishing means of guiding the carriage as it travels to and from the brick press, as I will hereinafter describe.

On the vertical members, 73 and 74, of the frame or carriage, 68, are bosses 75 and 76, which support a cam shaft, 77, said bosses being bored to fit said shaft and to permit the shaft to revolve in the same. Secured to the shaft, 77, are four cams, 78, 79, 80 and 81, which are secured to the shaft by set-screws, 82, but they may be otherwise secured if desired. It will be noticed that four cams are herein shown, this being because the present illustration is of a four-mold brick press, and if a greater or lesser number of molds are used, the number of cams will be correspondingly varied. It will be noticed, Fig. 1, that the cams are of different proportions, and that each of said cams operates its companion bell-crank by coming in contact with the roller, 23, on the outer end of the short arm, 21, of said bell-crank. The cams are provided with hubs which slip over the shaft, 77, and are secured by set-screws, 82, to said shaft. Projecting from the hubs of each of the aforesaid cams 78, 79, 80 and 81, are seg-

mental-tracks 83, 84, 85 and 86, each of which has a different throw for a purpose I will hereinafter state.

Forming a part of the frame, 29, are suitable bosses, 87 and 88, which form supports for a stationary shaft, 89, said shaft passing through the hubs of the bell-cranks, 19, 19', 19², 19³, thereby allowing said bell-cranks to oscillate on the stationary shaft. Also mounted on the shaft, 89, are suitable separating collars, 90, 91 and 92, which are for the purpose of holding the bell-cranks in proper position or in line with the brick-elevating heads, 9, before mentioned. By providing the cams of different throw and differential space and making the bell-cranks independent of the shaft, 89, it is obvious that the elevating-heads can be lifted to different heights, as shown by dotted lines in Fig. 1 and the purposes of which I will presently state.

Mounted on the ends of the shaft, 77, and secured thereto by means of keys or other well known devices are cranks, 93 and 94, Fig. 5, the outer ends of which are forked or bifurcated as shown at 95, 96, to receive the rollers, 101 and 102, which are mounted on pins, 97 and 98, which are in turn secured by cotter or other pins 99 and 100. The aforesaid rollers, 101 and 102, are designed to engage suitable stationary cams, 103 and 104, to cause the carriage, 68, with the cam-shaft 77, and the bell-crank shaft, 89 and bell-cranks, 19, to travel in the direction of the arrow. When the carriage has reached the limit of its movement in the direction of the arrow, the continued revolution of the shaft, 77, will cause the rollers, 101 and 102, to come in contact with other cams, 106 and 107, which are stationary cams secured to the guide-frames, 60 and 61, by bolts, 110 and 111, whereby the carriage, 68, with all of the parts mounted thereon is returned to its original position as shown in the side elevation, Fig. 1.

On the end of the shaft, 77, is mounted a bevel gear, 112, Figs. 5 and 6, adapted to mesh with a pinion, 113, said pinion being provided with an extended hub, 114, shown in section in Fig. 6, having a shoulder, 115, and a collar, 116, said extended hub forming a bearing and being supported in a journal-bearing, 116', which forms a part of the carriage, 68. The aforesaid pinion, 113, with its extended hub is bored to receive a shaft, 117, said shaft being provided with a spline which extends the length of the travel of the carriage plus the length of the pinion, and working in said spline is a feathered-key which is secured in the pinion, 113, whereby as the pinion is carried by the carriage along the shaft the key slides in the spline, which drives the pinion, 113, no matter what position the carriage may assume; the carriage is provided with an additional journal bearing, 118, for supporting said shaft, 117.

Suitably bolted to the base-plate, 58, are the pedestals, 119 and 120 the upper end of which forms journal bearings 121 and 122 for the shaft, 117, said shaft being held from lateral movement by the collars, 123 and 124 which are secured to said shaft by suitable means, as set-screws, not shown. Secured to the shaft, 117, is a member of a universal-coupling, 126, a companion member, 127, of this coupling being attached to the angle-shaft, 128, on the opposite end of the angle shaft is a coupling member, 129, which is connected with a companion member, 130 attached to a shaft, 132, supported in journal-bearings, 133 and 134, which form a part of a frame, 135, this frame being secured to a suitable foundation, 136, by bolts, 137, Fig. 5. The frame, 135, may, if convenient, be attached to or become a part of the main frame of the brick machine, but if not convenient, it can be arranged as herein described.

On the shaft, 132, is a bevel-gear, 138, which meshes with and is driven by a pinion, 139, mounted on a shaft 140, which in this particular case is the intermediate shaft of the brick machine. It may not always be convenient to arrange to drive the off-bearing attachment before described from this intermediate shaft of the brick machine as said machines are not all designed alike. I simply show this part of the mechanism to be driven from machines to which the device is to be attached, but other arrangements for driving the off bearing mechanism can be provided to suit conditions and without departing from the spirit of my invention.

Bolted to the foundation, 58, by bolts, 141 and 142, are two standards, 143 and 144, whose upper portions are provided with flanges, 145 and 146, through which pass bolts, 147 and 148, which secure the plate, 52, to the uprights, which plate, 52, has bolted to it at proper intervals the roller-supports, 149, 150 and 151, said supports being provided with flanges 152, through which the bolts pass to secure them to the plate, 52, said supports being also provided with hubs, 153 and 154, which are connected by overhead connections, 155, said hubs adapted as supports for the roller-shafts, 156. To the outer end of these last named shafts are mounted and secured the rollers, 157, and between the hubs or bearings, 153 and 154 and secured to the shafts, 156, are sprocket-wheels, 158, which are held in position by suitable means as by the set-screws, 159. It will be understood that each roller is provided with a shaft, sprocket and support, said sprockets being driven by a link-chain, 160, passing over the top of the same, and the lower portion of the chain being supported by rollers, 161, which revolve upon pins, 162, held in bosses 163, which form a part of the roller-supports, 149. The chain, 160, is

of the link-type and is driven over a sprocket, 164, Fig. 5, which is mounted on a shaft, 165, which in turn is driven by a conveyer-belt, 166, in the usual manner. By reference to Figs. 5 and 6 it will be observed that the rollers, 157, are spaced farther apart than the rollers, 167 and 168, which is due to the proper spacing of the rollers in relation to the brick molds and the elevating-heads, 7.

- 10 In the detail Figs. 7 and 8 I show a modification of the rollers and wherein the intermediate rollers, 170, between the elevating-heads, 7, are made smaller and I place two side by side as shown at 169, said rollers being 15 provided with sprocket-wheels and being driven as previously described, and the rollers being arranged to roll by the friction of the brick as they pass over the same. The advantage of the two rollers shown in Fig. 7 20 in place of one as shown in Fig. 6, is that if the brick has a tendency to wave as it passes over the rollers, 157, the two closely-arranged rollers, 169 and 170 will prevent this. It will also be observed that in Fig. 8, the link chain 25 has a slight elevation at the point marked 171, as it passes over the smaller rollers and this is for the purpose of holding the chain onto the small rollers. The sprockets, 180, being smaller than the sprockets, 158, and 30 the rollers, 169 and 170, also being smaller they should run faster so that the surface or periphery of the rollers should all travel about the same. The sprockets are so proportioned that they elevate the chain as 35 shown.

Referring to Fig. 9, which is a modification showing a direct elevating and turning device, said Fig. 9 shows the elevating bar, 11', and its hub, 7', as being immediately over the cam-shaft, 77, which is simply for the purpose of showing that the bell-crank, 19, might be dispensed with without departing from the scope of the present invention. Such a construction as shown in Fig. 9, 40 would also be a very simple way to design the machine, but the objection to it is that the brick would have to receive a second plunger or in other words the charger would push out brick as shown by "B," Fig. 9 and then 45 50 the next plunger would push the brick "B" to the opposite side of "B" by the brick "B" striking "B". These brick being green easily crumble which damages the brick by one brick coming in contact with 55 another to push the same out on the table, and thereby I deem it advisable to construct the machine with the bell-crank to operate the elevating-devices as shown in Fig. 1 in preference to the construction shown in Fig. 60 65 9. It is equally apparent that the brick can be pushed forward off of the table in the direction that the charger delivers them onto the table. They could also be received upon a belt to convey them away, but the inconvenience of supporting and carrying a belt

of sufficient width to carry four brick abreast as shown in Fig. 5 makes it almost impracticable for the purposes for which this attachment was designed. As the brick are to be conveyed long distances from the machine, 70 and as this off-bearing attachment is intended to be worked in connection with several machines located conveniently along one belt the impracticability of forcing the brick out onto a belt located in front of the 75 machine will be apparent, and in order to get them onto a narrow belt, it is necessary to reverse the brick from the direction that they are discharged from the molds by the charger. 80

In Fig. 1 the brick are supposed to be lying upon the table with their long sides parallel with the axis of the rollers, 157, and the mechanism previously described is designed to elevate the first brick to the dotted position at "C" and the second brick at "C'" 85 the third brick at "C²" and the fourth brick at "C³". This elevation of the brick one above the other permits the brick to be turned, with the heads 7, one being elevated 90 above the other and clear of the same. After they are carried over the live rollers, they are made to assume the position of "D", "D'", "D²", "D³" and when they are in this latter 95 position they are ready to be lowered onto the live rollers, 157, to be carried by the same and delivered to the conveyer-belt, 166. In order to allow the elevating-heads and their bars, 11, to pass between the rollers, 157, it is necessary to leave the ends 100 of the rollers, 157, overhang leaving openings between the same to permit the heads, 7, and their actuating rods, 11, to pass between the rollers.

The general operation of the apparatus 105 before described may be stated as follows: The conveyer, 166, is driven from a power plant and has a fixed speed. This conveyer is adapted to carry the brick any distance out on the plant. The conveyer, 166, revolves the sprocket-wheel 164 and shaft, 165, which drives the chain, 160, and thereby imparts revolution to the rollers in the supports, 149, 150, and 151. As the shaft, 140, of the brick press revolves, it turns the pinion, 139 and this revolves the gear, 138, which in turn revolves the shaft, 132, and shaft, 128, which through the universal coupling shown sets the shaft, 117, in motion. The revolution of the shaft, 117 gives 120 motion to the pinion, 113 and gear, 112, which is mounted on the shaft, 77. This latter shaft carries the cams, 78, 79, 80 and 81 and these coming in contact with the rollers, 23, of the bell-cranks, 19, the elevating- 125 rods, 11, are raised carrying with them the heads, 7, until the latter come in contact with the brick lying on the table, elevating all of the brick at the same time, each cam taking care of its own elevating-rod, bell- 130

crank, lifter-head and brick, the cam, 78, only lifting the first brick sufficient to clear the table; the next cam, 79, elevates the second brick sufficiently high to clear the 5 first one. The third brick is elevated by the third cam, 80, so that it clears the second one and the fourth cam, 81, elevates the fourth brick so that it clears the third, the several positions being shown in dotted lines 10 in Fig. 1. Now as the shaft, 77, begins to revolve the arms, 93 and 94, carrying the rollers, 101 and 102 come in contact with the cams, 103 and 104, thereby causing the carriage to travel in the direction of the 15 arrow "A", in Fig. 1, thereby passing the brick from the position shown in the drawings over the center of the rollers, 157. As the carriage passes from the original position to carry the brick into the position over the 20 rollers, 157, the enlarged portion, 48, of the arm, 47 comes in contact with the collar, 54, and this causes the bell-crank to swing on the pin 45, thereby operating the segmental-portion 42, and causing the same to shift 25 the rack-bar, 39, in a horizontal direction. This movement of the rack-bar through the segments 25 causes the sleeves 24, to revolve and as these sleeves are provided with square holes in which the square lifting rods are 30 mounted, the revolution of the sleeves is transmitted to the said lifting rods to thereby cause the lifting-heads, 7, to rotate. The spurs, 8, of these heads being embedded in the brick cause the brick to be turned 35 as shown by "D", "D'", "D''", "D'''", and at the same time the arms 78, 79, 80 and 81 being of different lifts and coming in contact with the roller of its companion bell-crank each bell-crank lifts its companion square lifting-rod, 11, elevating each 40 brick above the other, and as the carriage passes over the roller it delivers the brick in the position shown at "D", "D'", "D''", "D'''", at which time the cam 78, has revolved 45 sufficient to permit the roller, 23, to pass off of the cam and to assume its original position lowering the first brick onto the live rollers, 157, which carry them away. Shortly after the cam 79, allows its companion crank 50 to drop brick "D'" onto the live rollers to be carried which is followed by cam 80, and brick "D''", which in turn is followed by brick "D'''", which is permitted to drop later by the cam, 81. As the last brick 55 comes in contact with the rollers the elevating heads 7, are all lowered to a line shown in the position in Fig. 1, and then the rollers 101 and 102 come in contact with the cams 106 and 107 and return the carriage to 60 the position shown in said Fig. 1. As the carriage returns to its original position the enlarged end, 48, of the bell-crank, 47, comes in contact with the collar, 57 thereby causing it to rock on the pin, 45, to shift the rack 65 bar 39, and revolve the heads 7, and bring

them to their original position ready for the next operation.

Having thus described my invention what I claim as new and desire to secure by Letters Patent is:—

1. An attachment for a press, said attachment comprising a conveyer which is adapted for movement in a direction crosswise of the press, a support upon which the pressed article is delivered from the press, and carrier means for automatically removing the article from the support and transferring it to a point vertically over the conveyer and with its major axis substantially parallel with the direction of movement of the conveyer, said 70 conveyer including spaced rollers through the interspaces of which the carrier means operate to deposit the article thereon.

2. An attachment for a press, said attachment comprising a conveyer which is adapted 85 for movement transverse of the press, and a transfer-mechanism between the press and conveyer and operable in a horizontal plane substantially at right-angles with that of the conveyer and adapted to transfer the output 90 of the press to a point vertically over the conveyer and with its major axis substantially parallel with the direction of movement of the conveyer, said conveyer including rollers spaced apart to permit the transfer mechanism 95 to enter and operate through the space between adjacent rollers.

3. An attachment for a press, said attachment comprising a conveyer, and a transfer-mechanism between the same and the press, 100 said mechanism and the conveyer being operable in planes one substantially at right-angles with the other, and said conveyer comprising rollers spaced apart to permit the transfer mechanism to enter between the 105 ends thereof and place the brick vertically thereover.

4. The combination with a brick press of a carrier operable cross-wise of the front of the press, and a transfer-mechanism operable at right-angles with the direction of travel of the carrier and adapted to deliver the brick from the press to the carrier, said carrier comprising rollers spaced apart to permit the transfer mechanism to enter between the 110 ends of the rollers and carry the brick to a point vertically over the rollers.

5. The combination with a brick press, of a carrier operable in a direction which is cross-wise of the press, a supporting means upon 115 which the brick are received from the press, and a transfer-mechanism interposed between the press and the carrier and adapted to remove the brick from the support and transfer them to the carrier, said carrier including rollers spaced apart at the ends to permit the transfer mechanism to enter therebetween and place the brick vertically over said rollers.

6. The combination of a press, a carrier 120

extending cross-wise thereof, a transfer-mechanism between the press and carrier, said carrier comprising rollers spaced apart to permit the transfer mechanism to enter 5 therebetween, means for causing the transfer-mechanism to engage the brick, and means for moving the transfer-mechanism toward the carrier and into the space between adjacent rollers to enable the brick to 10 be deposited thereon.

7. An attachment for a press, said attachment comprising a conveyer, a transfer-mechanism between the same and the press, said conveyer comprising rollers spaced apart 15 at the ends to permit the transfer mechanism to enter between said ends, and means for operating the transfer-mechanism toward the conveyer, said transfer-mechanism having means for engaging and supporting the 20 output of the press during the transfer, and said operating means moving the supporting means into the space between adjacent rollers to carry the article into the vertical plane of the conveyer.

25 8. An attachment for a press, said attachment comprising a conveyer operable in a direction cross-wise of the press, a transfer-mechanism between the conveyer and the press, means for operating the transfer-mechanism toward the conveyer in a plane substantially at right-angles with the direction 30 of travel of said conveyer, said transfer-mechanism including means for engaging the output of the press and supporting the same 35 during the transfer, and said operating mechanism adapted to move the supporting means into the vertical plane of and above the conveyer, said conveyer including rollers spaced apart to admit the transfer mechanism, and means for operating the supporting means in a vertical direction relatively to the conveyer to deposit the supported article onto the latter.

40 9. An attachment for a press, said attachment comprising a conveyer operable in a direction cross-wise of the press, a transfer-mechanism between the conveyer and the press, means for operating the transfer-mechanism toward the conveyer in a plane substantially at right-angles with the direction 45 of travel of said conveyer, said transfer-mechanism including means for engaging the output of the press and supporting the same during the transfer, and said operating mechanism adapted to move the supporting means into the vertical plane of and above the conveyer, said conveyer including rollers spaced apart to admit the supporting means and means for operating the supporting means in 50 a vertical direction relatively to the rollers to deposit the supported article onto the latter, and means for causing the transfer-mechanism to recede from the rollers and return to 55 normal position.

60 65 10. Conveying mechanism for the output

of a press, said mechanism having in combination a conveyer, and a transfer-mechanism between the same and the press, adapted to engage the pressed article and carry the same to and deposit it upon the conveyer, and 70 complementary means for operating the conveyer and transfer mechanisms in planes one substantially at right-angles with the other, said conveyer including rollers spaced apart to receive the transfer mechanism, said transfer mechanism operating through the inter-space between the adjacent rollers. 75

11. An attachment for a brick-press said attachment comprising two conveying mechanisms operable in planes one substantially 80 at right-angles with the other, one of said mechanisms being interposed between the other conveying mechanism and the press and having means for engaging the pressed brick and transferring the same from the 85 press to the said other conveying means.

12. The combination with a brick press having a receiving table, of a horizontal series of parallel spaced rollers forming a conveyer in front of and operable cross-wise of 90 said table, and a transfer-mechanism between the conveyer and the table and operable through the table to remove the brick therefrom and elevate them and carry them to and deposit them upon the off-bearing 95 conveyer.

13. The combination with a receiving table of a press, of an off-bearing conveyer operating in front of and cross-wise of the table, said table having an opening over which the 100 pressed article is deposited, and a transfer-mechanism between the table and the conveyer and having a lifting-member which operates through the table to engage and lift the article thereon, and means for moving 105 the lifting-member toward the conveyer, and to a point vertically in line therewith, and means for depositing the article upon the conveyer, said conveyer having spaces to permit the lifting-member to operate vertically therethrough.

14. The combination with the receiving table of a brick-press, of an off-bearing conveyer operating in a direction cross-wise thereof, and a transfer-mechanism between the table and conveyer, said mechanism including a reciprocating carrier having a vertically disposed lifting member said table having an opening over which a brick is deposited, and means for operating said member to cause it to pass through the table opening and engage and elevate the brick, and means for operating the carrier in a plane substantially at right-angles with the direction of travel of the conveyer whereby 115 the lifting member and supported brick are advanced to a point over the conveyer. 120

15. The combination with the receiving table of a brick-press, said table having an opening over which the brick is deposited, of 130

an off-bearing conveyer operating in a direction cross-wise of the table, a transfer-mechanism between the conveyer and table and comprising a vertically-movable member normally disposed below the table in line with the opening therein, means for elevating said member to cause it to pass through the table opening and engage and elevate the brick, means for moving the elevating member in a horizontal plane substantially at right-angles with the direction of travel of the conveyer, said table being slotted in a direction toward the conveyer, and means for retracting the elevating member when it arrives over the conveyer to enable the brick to be deposited on said conveyer.

16. The combination with the receiving table of a brick-press, of an off-bearing conveyer, and a transfer-mechanism between said conveyer and table, said mechanism having a lifting - member which operates through the table to engage and elevate the brick, and means for moving said member toward the conveyer, said conveyer comprising rollers spaced apart to allow the lifting-member to enter therebetween and advance the brick to a point vertically thereover.

30 17. The combination with the receiving table of a brick-press, of an off-bearing conveyer, and a transfer-mechanism between said conveyer and table, said mechanism having a lifting - member which operates through the table to engage and elevate the brick, and means for moving said member toward the conveyer, said conveyer comprising rollers spaced apart to allow the lifting-member to enter therebetween and 40 advance the brick to a point vertically thereover, and means for withdrawing the lifting member relatively to the rollers and below the upper surface of the same whereby the brick is transferred to said rollers.

45 18. The combination with the receiving table of a brick-press, of an off-bearing conveyer, a transfer-mechanism between the table and conveyer, said table being slotted in a direction toward the conveyer and having an opening connecting with the slot and over which opening the brick is deposited, said mechanism comprising a lifting-member, means for advancing it through the table opening into contact with the brick, 55 means for moving the lifting-member substantially at right - angles with its first movement and toward the conveyer, said member operating in the slot of the table, and said conveyer comprising driven-rollers spaced apart to enable the lifting-member to enter therebetween and place the brick vertically thereover to be lowered onto the rollers.

60 19. The combination with the receiving table of a brick-press, of an off-bearing

mechanism comprising driven-rollers spaced apart and with the ends of the rollers toward the table forming open entrances between adjacent rollers, and a transfer-mechanism between the conveyer and the 70 table and having a member which operates vertically through the table to engage and elevate the brick, and means for operating said member to cause it to move parallel with the axis of the rollers and to enter between the rollers to deliver the brick thereover.

20. The combination with the receiving table of a brick-press, of an off-bearing mechanism comprising driven-rollers spaced apart 80 and with the ends of the rollers toward the table forming open entrances between adjacent rollers and a transfer-mechanism between the conveyer and the table and having a member which operates vertically through 85 the table to engage and elevate the brick, and means for operating said member to cause it to move parallel with the axis of the rollers and to enter between the rollers to deliver the brick thereover, and means for withdrawing 90 the member vertically into the space between the rollers whereby the brick is deposited on said rollers.

21. The combination of a receiving table having an opening therethrough and a slot 95 extending forwardly of said opening, a conveyer operating cross-wise of the front end of said table and comprising driven-rollers spaced apart to provide entrances between the inner ends of adjacent rollers, and a 100 transfer-mechanism between the rollers and table having a member adapted to remove the brick from the table and transfer it to the rollers, said member having a movement parallel with the axes of the rollers and adapted 105 to enter between the inner ends of the rollers, and said table having slots to accommodate said member.

22. A conveying mechanism of the character described having driven-rollers spaced apart to provide open spaces between the inner ends of adjacent rollers, a table upon which the article to be conveyed is deposited, said table having an opening through it and which extends toward the rollers, a transfer-mechanism having a member normally disposed below the table, means for moving said member vertically through the table opening so that it will engage and elevate the article placed thereover, means for moving said member along the table opening substantially parallel with the axes of the rollers and into the space between adjacent rollers, whereby the article is positioned above the rollers, and means for withdrawing the member into the space between the rollers and thereby lowering the article onto the rollers.

23. A conveying mechanism of the character described having driven-rollers spaced apart, means supporting the rollers so that 130

- they will overhang and provide open spaces between the inner ends of adjacent rollers, a slotted table having a receiving surface for the article to be conveyed, a carriage, a vertically-disposed lifting member connected to the carriage and movable in the slot of the table, means for elevating said member through the slot of the table to cause it to lift the article therefrom, means for moving the carriage in a horizontal direction to cause the lifting member to enter between the inner ends of the rollers and place the article over the rollers, and means for vertically withdrawing the lifting member and thereby lowering the article onto the rollers.
24. An attachment for a brick-press, said attachment comprising a conveyer having a movement in a direction transverse of the press, and a transfer-mechanism between the conveyer and press and comprising a plurality of individual lifting members each adapted to engage and support an article to be conveyed, and means for elevating the lifting members to different vertical heights whereby the articles are supported in different horizontal planes, means for advancing said members to the conveyer, and means for operating the members to cause them to deposit the articles onto the conveyer.
25. The combination with a brick-press having a table adapted to receive a plurality of pressed brick, of an off-bearing conveyer operable in a direction which is cross-wise of the table, a series of individual transfer-mechanisms one for each brick received upon the table, said mechanisms each including a lifting member, means for operating said members to cause them to engage and elevate the series of brick to variable heights so that they will lie in different horizontal planes, means for advancing said members to the conveyer so that the brick will overlie the latter, and means for lowering the brick independently and successively onto the conveyer.
26. The combination with a table adapted to receive a series of brick, of an off-bearing conveyer comprising rollers operable in a direction transverse of the table and spaced apart, a plurality of transfer-mechanisms one for each brick, and each having a lifting member which is operable through the table to engage a brick thereon, means for operating the lifting members to cause the brick to be elevated into planes one above the other, means for advancing the lifting-members toward and between said rollers with the brick supported above the rollers, and means for lowering the brick onto the rollers independently and successively.
27. The combination with a table adapted to receive a plurality of brick, of an off-bearing conveyer including rollers operable in a direction transverse of the table, a plurality of transfer-mechanisms, one for each brick

and each having a vertically guided lifting-member which operates through the table to engage and elevate one of said brick, means for operating the lifting-members to different heights above the table whereby the brick are moved into planes one above the other, means for imparting a partial rotation to the lifting-members to cause the brick to be given a quarter turn, means for advancing the lifting-members toward and between the inner ends of the rollers, with the brick above the rollers and in different planes, and means for lowering the brick onto the rollers independently and successively.

28. An attachment for a press comprising a conveyer, and transfer-mechanism between the same and the press, said mechanism and conveyer being operable in planes one substantially at right-angles with the other, and said transfer-mechanism including a series of lifting devices and means for elevating said devices in series and to variable heights.

29. An attachment for a press, said attachment comprising a conveyer, and a transfer-mechanism between the same and the press, said mechanism and the conveyer being operable in planes one substantially at right-angles with the other, and said mechanism comprising a series of lifting devices, means for lifting the same in unison but to variable heights, and means for moving said devices toward the conveyer.

30. An attachment for a press, said attachment comprising a conveyer, and a transfer-mechanism between the same and the press, said mechanism including a series of vertically-operating lifting-elements, and means for operating said elements in series to cause them to elevate the brick to progressively-increasing heights, and means for moving the transfer-mechanism toward the conveyer to enable the brick to be deposited thereon.

31. An attachment for a press, said attachment comprising a conveyer and a transfer-mechanism between the same and the press, said mechanism including a series of vertically-operating lifting devices arranged side by side, means for operating each of said devices independently but substantially in unison to cause the devices to be raised to variable heights, and means for moving the transfer-mechanism toward the conveyer to enable the brick to be deposited thereon.

32. The combination with a press having a slotted table for receiving the brick, a conveyer operating transverse of the press, and a transfer-mechanism between the press and conveyer, said mechanism including a series of vertically operating lifting-elements adapted to pass through the table and engage the brick thereon, means for operating the elements individually but substantially in unison, said means elevating the brick to variable heights, and means for moving the

transfer-mechanism toward the conveyer to enable the brick to be deposited thereon.

33. The combination with a brick press having a receiving-table, of an off-bearing conveyer in front and operable cross-wise of said table, and a transverse mechanism between the conveyer and the table, said table adapted to receive a plurality of brick and said mechanism including a corresponding plurality of lifting elements, and means for operating the elements in unison but to variable heights, to elevate one brick above the other, and means for moving the elements and supported brick into the vertical plane of the conveyer to enable the brick to be deposited onto the latter.

34. The combination with a brick press having a receiving table upon which a plurality of brick are adapted to be received, of an off-bearing conveyer in front of and operable cross-wise of said table, and a transfer-mechanism between the conveyer and the table, said mechanism including a vertically-operating lifting-element for each brick, a bell-crank lever connected to each of said lifting elements, and means for operating said levers substantially in unison to cause the lifting elements to be elevated in unison to variable heights.

35. The combination with a brick press having an elevating table upon which a plurality of brick are adapted to be received, of an off-bearing conveyer in front of and operable cross-wise of said table, and a transfer-mechanism between the conveyer and the table, said mechanism including a vertically-operating lifting element for each brick, a bell-crank lever connected to each of said lifting elements, and a series of cams placed side by side upon a common axis, each of the cams operating one of the levers and said cams being of increasing radius whereby the lifting elements are moved to progressively increasing heights, means for advancing said elements to the conveyer, and means for lowering the elements to cause them to deposit the brick onto the conveyer.

36. The combination of a brick press having a receiving table, said table having a plurality of openings over which individual brick are received, an off-bearing conveyer operable cross-wise of said table, a transfer-mechanism between the conveyer and the table, said mechanism including a series of vertically-disposed lifting-elements one of which is adapted to operate through each of the openings in the table and to engage a brick thereover, a series of bell-crank levers mounted on a common axis and each having one arm connected to one of the lifting-elements, and a series of cams of progressively increasing diameters mounted upon a common axis and adapted to engage the other arms of said levers whereby the lifting-ele-

ments are raised into different vertical heights to elevate the brick in planes one above the other, means for advancing the elements through the table-openings toward the conveyer, and means for operating said elements to cause them to deposit the brick onto the conveyer.

37. The combination with a brick-press having a receiving table provided with a plurality of openings arranged side by side, an off-bearing conveyer operable cross-wise of the table, and a series of transfer-mechanisms between the conveyer and the table and arranged side by side, said mechanisms corresponding in number to the number of table openings and each of said mechanisms including a vertically-disposed lifting-element operable through one of the table openings, a bell-crank lever having one arm connected to said element, a rotatable cam for operating the other arm of said lever, and means for advancing said element to the conveyer, said means including a reciprocating carriage to which the transfer-mechanisms are connected, stationary cams between which the carriage operates, and arms movable with the carriage and adapted to engage one set of said cams to move the carriage outwardly and thereby cause the series of lifting elements to be moved toward and into the vertical plane of the conveyer, and means for withdrawing the lifting-elements relatively to the conveyer to cause the brick to be deposited onto the latter.

38. The combination with the brick-press having a receiving table, of an off-bearing conveyer operable cross-wise of said table and a transfer-mechanism between the conveyer and the table, said mechanism having a series of vertically-operating lifting-elements adapted to remove the brick from the table and elevate them and carry them to a point over the conveyer, and means for imparting a partial rotation to the elements during the transfer to cause the brick to be turned from one position to another so that each brick will be deposited on the conveyer with its major axis parallel with the direction of movement of said conveyer.

39. The combination with a brick-press having a receiving table upon which a plurality of brick are placed side by side, an off-bearing conveyer operable cross-wise of said table, a series of individual transfer-mechanisms between the conveyer and the table and arranged side by side each of said mechanisms including a vertically-guided lifting element to operate through the table and engage a brick supported thereon, means for operating the lifting elements substantially in unison but to variable heights whereby the brick are lifted to different distances above the table, means for advancing said elements to the conveyer, and means for suc-

cessively lowering the elements whereby the brick are deposited one by one in succeeding order onto the conveyer.

40. The combination with a brick press 5 having a receiving table, of an off-bearing conveyer in front of and operable cross-wise of said table, and a transfer-mechanism between the conveyer and the table, said mechanism including a vertically-guided rod having 10 a head connected to its upper end and operable through the table, said head having spurs to engage a superposed brick, means for elevating the rod, means for advancing said rod horizontally to the conveyer, and 15 means for operating the rod to cause it to lower and thereby deposit the brick onto the conveyer.

41. In a brick press having a table upon which a plurality of brick are received, 20 means for engaging and elevating said brick one above the other to successively increasing distances above the table, a conveyer, and means for depositing the elevated brick successively thereon.

25 42. The combination with the receiving table of a brick press said table adapted to receive a plurality of brick, of a plurality of vertically-operating lifting-members operating through the table to engage and elevate 30 the brick to successively increasing distances above the table, a conveyer, and means for advancing the elevated brick thereto.

43. The combination, of the receiving table of a brick press said table adapted to 35 receive a plurality of brick side by side, vertically-operating lifting-members movable through the table to engage and elevate the brick to successively increasing distances above the table, means for partially rotating 40 the members to cause the brick to be given a quarter-turn, a conveyer, and means for advancing the brick thereto.

44. The combination with the receiving table of a brick press, said table adapted to 45 receive a plurality of brick side by side, vertically-operating lifting-members movable through the table to engage and elevate the brick to successively increasing distances above the table, means for partially rotating 50 the members to cause the brick to be given a quarter-turn, a conveyer, means for advancing the brick thereto, and means for depositing the brick independently and successively onto the conveyer.

55 45. The combination with the receiving table of a brick press said table adapted to receive a plurality of brick side by side, vertically-operating lifting-members, one for each brick and movable through the table to 60 engage and elevate the brick to successively increasing distances above the table, a conveyer comprising rollers spaced apart and operating transverse of the table, means for advancing the lifting-members toward the 65 conveyer and between the rollers thereof

whereby the brick are disposed above the rollers, means for partially rotating the members to cause the brick to be given a quarter-turn so that they will travel endwise on the conveyer, and means for independently and successively depositing the brick onto the rollers.

46. The combination with the receiving table of a brick press said table adapted to receive a plurality of brick, of vertically-operating lifting-members movable through the table to engage and elevate the brick to successively increasing distances above the table, a conveyer comprising rollers spaced apart and turnable transversely of the table, 75 means for advancing the lifting-members toward the rollers in a direction parallel with the axis thereof, said lifting-members entering the space between the rollers and supporting the brick vertically above the rollers, 80 means for rotating the members to cause the brick to be given a quarter-turn so that they will travel endwise on the conveyer, and means for independently and successively lowering the brick onto the rollers, said last-named means comprising a series of cams whose operating surfaces are of different lengths.

47. The combination with the receiving table of a brick press said table adapted to 95 receive a plurality of brick, of vertically-operating lifting-members movable through the table to engage the brick, a series of cams of variable throw and a corresponding series of bell-crank levers for operating the lifting-members to elevate the brick to successively increasing distances above the table, means for partially rotating the members while elevated to cause the brick to be given a quarter-turn, a conveyer, means for advancing the lifting-members thereto, and means for lowering the brick independently and successively onto the conveyer so that they will travel endwise thereover.

48. The combination with the receiving table of a brick press adapted to receive a plurality of brick side by side, said table being provided with openings, of lifting-elements normally disposed below the table in line with said openings, each of said elements 110 comprising a vertically-guided rod angular in cross section, and having a lifting head on its upper end, a vertical sleeve through which the rod operates, said sleeve provided with a toothed-segment, and means for operating the segment to cause the sleeve and its rod to be axially turned.

49. The combination with the receiving table of a brick press adapted to receive a plurality of brick side by side, said table being provided with openings, of lifting-elements normally disposed below the table in line with said openings, each of said elements comprising a vertically-guided rod angular 115 in cross-section and having a lifting-head on 120

130

its upper end, a vertical sleeve through which the rod operates, said sleeve provided with a toothed-segment, and means for operating the segments to cause the sleeve and its rod 5 to be axially turned, said last-named means including a horizontal guided rack-bar engaging the segment, and means for shifting the rack-bar in a horizontal direction.

50. The combination with the receiving 10 table of a brick press, said table adapted to receive a plurality of brick side by side, of a plurality of vertically-operating lifting-members each normally disposed below the table in line with a brick, said table having openings 15 through which the members operate, a conveyer operating cross-wise of the table and in front thereof, a reciprocating carriage, supports therefrom having sleeves through which the lifting-members operate, a bell- 20 crank lever and a coacting cam for operating each of the lifting members, said cams being arranged to elevate the lifting members to successively increasing distances above the table, a rotatable shaft upon which the cams 25 are mounted, arms fixed on said shaft, stationary cams disposed on each side of the shaft and alternately engaged by said arms to move the carriage in alternate directions, whereby the lifting-elements are moved toward 30 the conveyer and are thence returned toward the table, means for axially-turning the lifting-members during the transfer of the brick from the receiving table to a point over the conveyer, and means for causing the 35 lifting-members to independently and successively lower the brick onto the conveyer.

51. The combination with the receiving table of a brick press, and a conveyer operating cross-wise of the table, of a transfer- 40 mechanism between the conveyer and table, said mechanism including a stationary guide-frame, a carriage adapted to reciprocate in said frame, a driven shaft mounted in the carriage, a series of vertically-guided lifting- 45 rods normally below the table and in line with openings therein, guides supported on the carriage and in each of which a lifting arm operates, independent cam-mechanism and bell-crank levers for operating the lifting- 50 rods to cause them to elevate the brick to successively increasing distances above the table, means for imparting a movement in one direction to the carriage to cause the lifting-elements to be moved toward the conveyer with the brick superposed thereover, said cam-mechanism operating to independently and successively lower the lifting-rods whereby the brick are deposited one by one upon the conveyer, and means for giving a 55 return motion to the carriage whereby the lifting-rods are caused to assume a normal position beneath the table.

52. The combination with the receiving 60 table of a brick press, and a conveyer operating cross-wise of the table, of a transfer-

mechanism between the conveyer and table, said mechanism including a stationary guide-frame, a carriage adapted to reciprocate in said frame, a driven-shaft mounted in the carriage, a series of vertically-guided lifting- 70 rods normally below the table and in line with openings therein, guides supported on the carriage and in each of which one of the lifting arms operates, independent cam mechanism and bell crank levers for operat- 75 ing the lifting rods to cause them to elevate the brick to successively increasing distances above the table, means for imparting a partial rotation to the lifting-rods whereby the brick are given a quarter-turn and are adapt- 80 ed to be placed on the conveyer with their greatest length in the direction of travel of the latter, means for imparting a movement in one direction to the carriage to cause the lifting-elements to be moved toward the conveyer with the brick superposed thereover, said cam-mechanism operating to independ- 85 ently and successively lower the lifting-rods whereby the brick are deposited one by one upon the conveyer, and means for giving a 90 return motion to the carriage whereby the lifting-rods are caused to assume a normal position beneath the table.

53. The combination with the receiving 95 table of a brick press, of an off-bearing conveyer, a guide frame, a carriage adapted to reciprocate in said frame, vertically slidable lifting-rods mounted in guides on the carriage and having heads to operate through the table and engage the brick thereover, 100 cams and bell-crank levers for operating the lifting-rods to successively increasing distances above the table, stationary cams at one side of the carriage and revoluble arms movable with the carriage and engaging said 105 cams for moving the carriage in its guide-frame and thereby advancing the lifting-rods to the conveyer with the brick superposed over the latter, said cams permitting the withdrawal of the lifting-rods in sequence 110 whereby the brick are independently and successively lowered onto the conveyer, and other stationary cams at the other side of the carriage engaged by said revoluble arms to return the carriage and its adjuncts to 115 normal position.

54. The combination with the receiving 120 table of a brick press, of an off-bearing conveyer, and a transfer-mechanism between the table and conveyer, said mechanism comprising a reciprocating carriage, a shaft journaled therein and provided with independent cams, independent bell-crank mechanisms engaged by said cams, independent lifting-rods connected with said levers and operated by the cams to elevate the brick to successively increasing distances above the table, means for moving the carriage in one direction to cause the lifting-devices and brick to be moved toward the conveyer, a 125 130

shaft extending at right-angles with the cam-shaft, a pinion adapted to slide relative to said second shaft, a gear-wheel on the cam shaft engaged by said pinion, said pinion 5 having a projecting hub which is journaled in a bearing forming part of the carriage whereby the pinion travels with the carriage during its reciprocations and is maintained in engagement with said gear-wheel at all 10 positions that the carriage may assume, means for operating the second-named shaft, said pinion continuously revolving the cam-shaft, and means for returning the carriage and its associated parts to normal position. 15 55. The combination with the receiving table of a brick press said table having openings through it, of a reciprocating carriage, a lifting - mechanism comprising vertically-guided rods having lifting-heads operable 20 through the table to engage and support the

brick thereon, mechanism for raising and lowering said rods, guides fixed to the carriage and sleeves mounted in said guides and receiving said rods, segmental-gears fixed to the sleeves, a horizontal rack-bar engaging 25 said gears, a vertically-pivoted arm carried by the carriage and having a segmental toothed portion to engage said rack-bar, a guide for said pivoted arm, and a stop on the guide interposed in the range of action of the 30 arm and adapted to rock said arm to impart movement to the rack-bar and rotation to the lifting bars.

In testimony whereof I affix my signature in presence of two witnesses.

WILLIAM R. CUNNINGHAM.
